(57) **CLAIM**

The ornamental design for an outdoor communications cabinet, as shown and described.

DESCRIPTION

FIG. 1 is a perspective view thereof;

FIG. 2 is a top view thereof;

FIG. 3 is a bottom view thereof;

FIG. 4 is a front view thereof;

FIG. 5 is a back view thereof;

FIG. 6 is a right side view thereof; and,

FIG. 7 is a left side view thereof.

The characteristic features of the design reside in the shape and ornamentation of the entire cabinet as shown in the drawings.
